UNITED STATES PATENT OFFICE.

GEORGE H. HUSE, OF BOSTON, MASSACHUSETTS.

CANOPY-TOP FOR CHIMNEYS.

SPECIFICATION forming part of Letters Patent No. 760,992, dated May 24, 1904.

Application filed October 19, 1903. Serial No. 177,585. (No model.)

To all whom it may concern:

Be it known that I, GEORGE H. HUSE, of Boston, county of Suffolk, State of Massachusetts, have invented an Improvement in Canopy-Tops for Chimneys, of which the following description, in connection with the accompanying drawings, is a specification, like characters on the drawings representing like parts.

This invention has for its object to construct an improved canopy-top for chimneys which can be collapsed or folded in such a manner as to occupy but little space for the purpose of shipping, and which will present a slightly appearance when in use, and which may be cheaply manufactured.

Figure 1 shows in side elevation a canopy-top for chimneys embodying this invention. Fig. 2 is a side elevation of the device, showing the top plate in section. Fig. 3 is a plan view of the frame, the top plate being removed. Fig. 4 is a side view of the frame with the parts thereof folded in position for shipping. Fig. 5 is a plan view of the top plate. Fig. 6 is a vertical sectional detail of a portion of the frame and top plate, showing the connections for the parts; and Fig. 7 is a detail to be referred to.

a represents the top plate, which is made circular and slightly conical. This plate is made of two or more pieces of mica, the adjoining edges of which are overlapped and secured together by rivets *a'*, and said pieces are also secured together at the center by a gromet *a''*.

The frame of the canopy-top consists of a plurality of legs *b*, pivotally connected together. The legs are composed of wire of small gage, so as to present a slightly appearance, and said legs are bent at their upper ends to form eyes *b'*, and they are also bent angularly to provide a plate-receiving portion and uprights therefor. Three legs are herein shown, and the eyes *b'* of the several legs are superimposed upon a gromet *b''*. The eyes are made large enough to turn freely on the gromet, which latter serves as a pivot. At the lower end of each leg a sheet-metal chimney-engaging clip *c* is secured, which is adapted to engage the top of the chimney *f*. These clips are made of a width to provide for a firm

engagement with the chimney and to afford a good and sufficient bearing thereon, and they are herein shown as secured to the ends of the legs by striking up oblong portions *c'* in such a manner as to provide a hole at each end of the portion so struck up and then driving the end of the wire leg through said holes beneath the struck-up portion, as represented in Fig. 7. The chimney-engaging clips are thereby firmly secured to the ends of the wire legs. The top plate is detachably secured to the frame by a detachable fastening *d*, which passes through the gromet *a''* and also through the gromet *b''*.

For shipping the device the top plate is removed and the several legs comprising the frame are turned on the pivot and brought into position to occupy substantially the same plane as represented in Fig. 4, and when so folded or collapsed they will occupy but little space, so as to be packed snugly in a box. The detached top plates will nest together in the box, and therefore will occupy but little space.

Having thus described my invention, what I claim as new, and desire to secure by Letters Patent, is—

1. A canopy-top for chimneys consisting of a collapsible frame having a central gromet, a detachable top plate consisting of several pieces of mica secured together by rivets and by a central gromet, and a detachable fastening for attaching said top plate to the frame, substantially as described.

2. A canopy-top for chimneys consisting of a collapsible frame comprising a plurality of wire legs having eyes at their upper ends, and having sheet-metal chimney-engaging clips at their lower ends, a centrally-disposed gromet on which the eyes of the several legs are superimposed, and on which they freely turn, and a detachable top plate secured to said frame, substantially as described.

3. A canopy-top for chimneys consisting of a collapsible frame comprising a plurality of wire legs having eyes at their upper ends and having sheet-metal chimney-engaging clips at their lower ends formed with struck-up oblong portions having holes at each end which

receive the lower ends of the wire legs, a centrally-disposed gromet upon which the eyes of the several legs are superimposed, a top plate having a central gromet, and a detachable fastening passing through the gromet of the top plate and through the gromet of the frame, substantially as described.

In testimony whereof I have signed my name to this specification in the presence of two subscribing witnesses.

GEO. H. HUSE.
